METHOD OF CONFORMING EXTENSIBLE MATERIAL

1,313,916.

Specification of Letters Patent. Patented Aug. 26, 1919.

Application filed October 2, 1917. Serial No. 194,395.

To all whom it may concern:

Be it known that we, ARTHUR L. RUSSELL and CHARLES E. GRUSH, citizens of the United States, residing at Boston, in the county of Suffolk, and at Beverly, in the county of Essex, State of Massachusetts, respectively, have invented certain Improvements in Methods of Conforming Extensible Material, of which the following description, in connection with the accompanying drawings, is a specification, like reference characters on the drawings indicating like parts in the several figures.

This invention relates to the manufacture of articles which are generally to conform to surfaces over which they are to be placed, and in particular to methods of thus shaping extensible material to effect an economy thereof, a reduction in labor costs, and improvements in the fit of the articles.

In one aspect the invention comprises a method of operating upon the material in such a manner as to effect local interior fullness by subjecting said material to repeated tensioning operations which are applied upon the same, adjacent or successive portions and which, in the aggregate, produce a greater effect over the desired interior area than at the edge portions. The method comprises subjecting a small area only of the stock to tension at a time, relieving the tension, and then subjecting the same or an adjacent portion of the stock to tension during the continuous application of repeated pulling or stretching operations, to the end that interiorly located areas of the upper may be permanently stretched. By thus stretching to a greater or a less extent, according to the number of pulling operations which are applied to a given area, the interior portions of a sheet of material, the same may be permanently stretched before application to a form, and be thereby made to fit truly its varying contour. An example of the beneficial effects of treating material in the manner contemplated by this method is found in its adaptability for fitting the upper of a shoe to the high toes and the low balls and deep shanks of modern lasts. The method may be practised either by the manipulation of simple tools in the hands of an operator, or by a suitable machine. In either case a portion of stock will be engaged at adjacent points and, by movement

of the engaging means relatively apart, the intervening portion of the stock will be stretched in the direction relatively to the length of the last which is required to make the upper fit over the particular portion of the last upon which it is to be applied. Machines which are well adapted to carry out the steps of the present method are shown, described, and claimed in our prior applications for U. S. Letters Patents, Serial No. 827,609, filed March 27, 1914, and Serial No. 109,664, filed July 17, 1916, of which applications the present application is in part a continuation.

If the method is carried out by the operation of simple implements in the hands of the operator, the stock will be engaged at adjacent points, and will by the movement of the engaging means relatively apart, be stretched locally to the required extent, and at the desired points within the edges of the stock, in the same manner as contemplated by the machines of the applications above referred to.

In practising the method the stretching of the stock may advantageously be performed by any suitable stock seizing means whose movements are controlled by hand or otherwise to supply the tension at the desired points and to the extent required for each area being stretched. The seizing means may be in the form of two pincers whose jaws are spaced apart at appropriate distances and are adapted to seize adjacent portions of the stock, to be moved apart for stretching the stock, and to then retract, and also to separate and release the stock. Under one aspect of the method the stock, after being seized and stretched by applying tension to an area lying between the points of seizure, is held under tension for a suitable interval between the stretching movements, and is thereafter released. By repeated applications of the stretching action to the same, or adjacent portions of the stock, and by holding the stock under tension following each of said applications, the stretched condition of the stock becomes permanent, whereby it may be caused to conform to the varying curvatures of the surface of the last, and to maintain the shape thereof in the finished shoe.

The method will be explained in connection with two forms of machine which are

substantially the same as those disclosed in our prior applications above referred to, and embody suitable instrumentalities for carrying the method into effect. It is to be understood, however, that the method may also be practised by other forms of machine, or by hand, and the performance of its several steps is in no sense limited to the machines herein illustrated by way of example only.

10 Referring to the accompanying drawings:

Figure 1 is a view in side elevation partly sectional, illustrating the operative parts of one form of machine by which the method may be practised, and

15 Fig. 2 is a view in side elevation, partly sectional, of another form of machine by which the method may be practised.

Referring to Fig. 1, a suitable frame or 20 base 3, a portion of which is illustrated, sustains bearings for a driving shaft 6 which is driven by power derived from a suitable source. The frame of the machine also supports a work table 10 provided with a slot 25 or opening 12 located interiorly of its edges and preferably about at its center.

The stock engaging or gripping devices 30 comprise upper jaw carrying arms 20, 24, respectively, which extend over the table 10 and lower jaw carrying arms 22, 26, extending under the table, each lower arm having a foot 65 which is guided in suitable guideways carried by the frame for movement lengthwise of the arms toward and 35 from the opening 12 in the table. The lower arms 22, 26, carry fixed pincer jaws 28, 30, which project upwardly through the opening 12 in the table and hold the work raised slightly above the face of the table as indicated in the drawings by dotted lines. The upper arms 20, 24 carry, respectively, cooperating jaws 32, 34 each of which is suspended from its arm by a pair of parallel links 36, 37, and 38, 39, Fig. 1. 40 These links are inclined outwardly so that as the pincers are moved apart one toward the left and the other toward the right they will be caused by the pull of the stock to grip or hold the latter with increasing force.

50 The initial grip of the stock is produced by the closing springs 49, which surround a rod 44 and act against upward extensions 40, 41 of one link 36, 39, of each pincer. The extensions 40, 41, constitute levers which are arranged to be pressed together between the thumb and forefinger of one hand to raise the two upper jaws 32, 34, simultaneously to permit the insertion of the work between the two pairs of jaws.

55 The rod 44 passes loosely through the lever extensions 40, 41 at 42, 43, and on its oppositely threaded end portions the rod carries adjustable abutments 45, 46, against which the lever extensions strike near the 60 outer ends of the pincer pulling movements.

By this engagement with the stops 45 the links 36, 37 and 38, 39 are turned in the direction to lift the jaws 32, 34 and release their grip on the work.

The points in their stroke in which this release occurs and therefore the length of the upper pulling or stretching movements is determined by the positions of the stops 45 and this can be adjusted by turning the rod which for this purpose has a rigid collar 47 with radial holes for application of an instrument by which to rotate the rod. The stops 45 are prevented from turning by square heads that have a sliding fit between the side plates of the arms 20, 24.

80 The pincers are caused to reciprocate, toward and away from each other, in order that the jaws may be made to engage with and grip interior portions of the leather and other stock being stretched. As herein shown, this reciprocating movement of the pincers is effected through links 67, between the lower arms 22, 26 of the pincers and a reciprocating bar 68, the latter being operated by a crank pin 72 of a crank disk on the front end of the power shaft 6. Preferably the bar has a cam slot 70 in which the crank pin works to accelerate the movement of the pincers during the first portion of the throw of the crank and to retard it before the return stroke begins, the object being to obtain a quick grip of the stock and an initial stretch with a slow final stretch nearly to a dwell. The designing of the cam slot 70 is shown as such that when the crank pin 100 starts downwardly from the position in which it is shown, for example toward the left, the links 67 will be caused to straighten; thus separating the two pincers. When the latter begin to separate the jaws will grip 105 and pull the upper leather, the crank pin operating along the upwardly inclined lower face of the left hand portion of the slot 70. During the second 90° of its throw the crank pin moves backwardly down the cam slot 110 toward its middle and the bar 68 and pincers are slowly moved during the second quarter of the crank throw a distance equal to the difference between the length of the crank throw and the length of the cam incline. 115 Of course it will be understood that differently shaped cams may be adopted for different classes of work.

With this machine the pincers may be caused to feed the work automatically toward the right or toward the left during the stretching operation. This is accomplished by decreasing the force of the gripping action of the jaws of one pincer upon the stock during the pulling movement while the jaws 125 of the other pincer continue to grip the work whereby the work is moved in the direction toward which the jaws of the latter pincer are traveling. The rod 44 carrying the stops is adjustable endwise, through the 130

levers 40, 41 to locate one or the other stop farther from the gripping point according to the direction of feed desired.

The rod 44 has a fixed collar 46 between which and the collar 47 is located an arm 48 of a rock shaft 50 mounted in a bearing arm of the frame. At its rear end the rock shaft 50 has an arm 52 having the lost motion provided between the stops *a* and *c* on 10 the arm and a fixed stop *b* which is rigid with the rock shaft. The free end of arm 52 is connected pivotally to a rod 54 which latter in turn is connected by a ball and socket joint with an angle lever 56 on 15 which is a knee fork 58 through which the operator can rock the shaft 50 to place one stop 45 nearer than the other to its lever 40 or 41. In such position the nearer stop 45 will cause its coöperating lever to lift its 20 jaw 32 or 34 while the other jaw continues to grip the stock with maximum force. The pincer so gripping the stock will therefore feed the stock in the direction of its movement at the end of each stretching movement 25 of the pincers and therefore will present a fresh portion of stock to be gripped and stretched at each operation of the machine. The direction of feed is determined by the direction of movement of the knee fork 58 and the length of the feed is determined by the extent of movement of the knee fork. The lost motion at *a*, *b*, *c* prevents feeding when manual manipulation of 30 the work by the operator's hands is preferred. Springs 60, 60 above and below the guide 57 center the knee fork normally. A spring plunger 63 having a tapering head located in a V-shaped notch in arm 48 normally centers the rock shaft 50.

40 In the practice of the method by the use of this machine, the operator first inserts the work, after having pressed inwardly upon the handle extensions 40, 41 which raises the movable jaws of the pincers by 45 the parallel links. In placing the shoe upper or sheet of stock on the work table, it will be seen that the operator may locate the stock in such position that the interior area which is to be stretched may be selected by 50 positioning such area at the proper point for the pincers to operate thereon. When the work has been so positioned the handles 40, 41 are released and the springs 49 will cause the upper jaws to clamp the work against 55 the lower jaws of the pincers with a light yielding pressure. When the machine is started by the actuation of a clutch, or other suitable instrumentality, the pincers will be reciprocated inward and outward 60 and the work will be gripped and stretched as the pincers separate, and released from the gripping action of the pincers as the latter approach each other, these actions being repeated a suitable number of times, 65 at the will of the operator, until the desired

amount of stretching has been accomplished. The work is manually held smooth and in slight frictional contact with the table and as the pincers move outward to stretch the stock which has been seized by the jaws 70 thereof, such movement will continue until the lever extensions 40, 41 or either of them strike the release stops 45, following which if one release stop is struck first the stock 75 will be fed toward the other one by the continued pull of the pincer associated with said other stop. Upon a reverse or inward movement of the pincers the movable jaws 32, 34 will, by reason of the inclined position of their supporting links slide over the 80 stock, which latter will be reengaged by the jaws and further stretched when the pincers again move outwardly.

The machine illustrated in Fig. 2 comprises a frame 74 having a base 76 in which 85 is supported the internally threaded hub 78 of a hand wheel 80, the hub being formed with an external groove 82, which receives a lug 84 projecting from a plate which is clamped to the base. A work table 86 90 has a base 88 which is rigid with a screw stem 90 having a coarse thread, and fitting the internal thread of the hub 78. The stem 90 has a vertical slot 92 which receives a 95 guide pin 94 projecting rigidly from the frame base, said parts serving to prevent rotation of the screw stem. By turning the hand wheel the screw stem will be caused to feed up or down according to the direction of rotation and the work table may thus 100 be adjusted to locate its work-receiving surface in the desired relation to the plane of the pincer jaws. During the rotation of the hand wheel engagement of the lug 84 with the groove 82 will prevent vertical movement 105 of the hand wheel.

The upper part of the machine frame supports bearings for a driving shaft carrying a pulley 96 to which may be applied a belt for receiving power from a suitable source. 110 The pulley shaft carries a disk having a crank pin 98 thereon which runs in a cam groove 99, in a cam block 100. The cam block operates a plunger 102 which is guided for reciprocating movements by a plate 104, 115 bolted to the frame, and by a stem 106 rigid with the upper part of the cam block and guided by a plate 108 which is likewise bolted to the frame. There is a yielding lost motion connection between the stem and 120 plunger, as shown in the drawing, and the plunger 102 sustains, by a pivot 110, the two jaw-supporting links 112, 112, which respectively sustain through pivots each of the upper pincer jaws 114, 114, whose lower 125 faces are constructed to frictionally engage the stock. The links 112 have divergently extending upper end portions 116 which are normally acted upon by a spring 118 which holds the jaw pressed toward each other and 130

against the stop 120 and thereby maintains the jaws spaced a suitable distance from each other, and leaf springs 122, 122, are secured to the links 112, 112, and bear at their free ends against the jaws 114, 114, to thereby hold them yieldingly with their faces in substantial parallelism with the faces of the other pincer jaws 124, 124.

The pincer jaws 124, 124, which if they are to engage the inner side of the leather stock preferably have their faces roughened slightly to prevent slipping, project through an opening 126 in the work table 86, and are supported by links 128, 128 whose lower ends are sustained by a single pivot 130, from the table base 88. The links 128 are provided with aligned horizontal perforations through which passes an adjusting rod 132, having at its outer free end a knurled or roughened handle 134. The rod is encircled by a spring 136 that holds the jaws 124, 124 normally apart and the rod has right and left hand external screw threads engaging internal screw threads in two spaced nuts 138, 138, which are provided with pins 140, 140, moving in guiding slots formed in two sleeves 142, 142. These sleeves are bored to receive the nuts 138 and are also formed at their inner ends with forked portions which embrace the links 128. Spiral springs 144, are located in the bores of the sleeves between the inner ends of the nuts and the bottoms of said bores and hold the jaws normally in the position shown until the stock has been gripped between the upper and the lower jaws. The springs will then yield and permit the jaws to separate and stretch the stock. The springs 144 return the jaws to their initial position after their stretching operation. By turning the handle 134, the tension of the springs may be adjusted in order to apply different degrees of force to the stock, prior to the separation of the pincers for stretching the stock.

The cam groove 99 is formed with a substantially flat or horizontal portion 99^a along which the crank pin 98 acts during about one-half of the cycle, which moves the plunger 102 and pincer jaws 114, 114 downwardly to clamp the work against the jaws 124, 124, and, by continued downward movement, causes the pincers to move apart and stretch the stock. The maximum movement of the pincer to stretch the stock occurs at the time that the pin 98 reaches its lowest point. Thereafter the pin enters the substantially concentric portion 99^b of the cam groove which produces a dwell, thus maintaining the stock stretched for an interval of time which tends to render the stretching permanent. Thereafter the crank pin reaches the end of the curved portion 99^b of the groove, and, for the remaining one-quarter of its stroke the crank pin acts to quickly raise the plunger 102, thus causing

a rapid release of the stock from the gripping action of the pincers. This is especially advantageous in that it tends to prevent any drag of the pincer jaws over the stock during the inward movement of the jaws as 70 they are lifted instantly from the work.

In practising the method with this machine, a piece of leather stock is placed upon the work table with the portion which is to be stretched located between the pincer jaws. 75 Power being then applied, through a belt or other suitable means, to the pulley 96 and the crank pin being at its highest point, said crank pin first causes a depression of the plunger carrying the jaws 114, 114, the stock being 80 gripped between these and the co-operating jaws, and further movement of the plunger effects a separation of the pincers to stretch the stock, with a suitable dwell at the end of the stretching movement, and thereafter a 85 lifting of the pincer jaws 114 to release the stock. If the machine continues to operate while the stock remains in one position the same area may be subjected to a plurality of successive tensioning operations until the 90 desired amount of stretching has been attained. The operator may then move the stock to a different position and subject a different area to as many successive tensioning impulses as may be desired. The upper 95 may not only be stretched along parallel lines back and forth by feeding the stock properly by hand during the intervals between the pulling movements of the pincers, but the work may be turned so as to obtain 100 successive stretching effects in different directions, as when shaping a toe cap to fit over the toe end of a last. In shaping an upper to fit the last back of a high toe to prevent bridging from the toe to the instep 105 a stretching in a direction lengthwise of the last only is required to present an amount of fullness sufficient to permit the upper to enter the hollow of the last. Similarly in shaping shank portions of a shoe upper 110 where it is desired to make the leather fit a narrow shank last the direction of stretching will be mainly lengthwise and may be made greater at the edge of the stock and gradually diminishing to a point remote 115 from the edge. This gradation of the stretching action is obtainable by feeding the stock along by hand at the proper rate during the continuous operation of the stretching instrumentalities, the rate of feed 120 being increased as the operation progresses farther from the edge of the stock.

The method of treatment hereinbefore set forth is obviously not necessarily associated with either of the above described machines, 125 other than that said machines embody convenient instrumentalities for carrying the method into effect, and are capable of doing this with greater rapidity, and of applying more stretching force to the stock than if the 130

method were performed by simple hand tools, for example. It is nevertheless a fact, however, that the method is capable of performance by a large variety of machines, tools, or implements, and the practice thereof is in no sense limited to any particular form of apparatus, machine, or instrumentality.

Having described our invention, what we claim as new and desire to secure by Letters Patent of the United States is:

1. The method of conforming extensible material which consists in subjecting said material to successive stretchings, the aggregate tension applied being greatest over a predetermined interior portion located at a substantial distance from the edge portions, thereby producing fullness of such interior portion.

2. A method of stretching leather or similar stock, which comprises subjecting a limited interior portion of the stock remote from and which does not include its edge portions to repeated pulling operations to effect fullness of a predetermined interior area of the stock for enabling it to fit over a curved surface.

3. A method of treating shoe upper stock to provide it with local fullness for enabling the stock to conform with the inequalities of surface of a last, comprising seizing the stock at points located wholly within its edge portions and applying to the stock a plurality of stock-tensioning operations to permanently stretch it only at those portions where local fullness is desired.

4. A method of treating stock for effecting local fullness to cause the stock to fit over varying surfaces, comprising engaging the stock at adjacent points located wholly within the edge portions of the stock, and repeatedly tensioning the stock between the points of engagement until permanent fullness of the tensioned area only is effected.

5. A method of stretching stock for effecting local fullness to cause the stock to fit over varying surfaces, comprising engaging an interior portion of the stock at a plurality of points, applying tension to an area of the stock lying between the engaged portions, holding the stock under tension a sufficient time to produce a permanent stretch, releasing the stock, engaging fresh portions and repeating the operations until the desired amount of fullness is effected.

6. A method of stretching stock for effecting local fullness to cause the stock to

fit over varying surfaces, comprising seizing the stock at separated points, pulling the stock so as to stretch an area thereof, releasing the stock and repeating the operations by applying the pulling strain in different directions over the area being stretched, the complete stretching being confined to an area lying within the edge portions of the stock to provide a permanent condition of fullness in such area.

7. A method of treating stock, comprising engaging the stock at points located interiorly of its edge portions, moving the engaging means apart to stretch the stock, releasing the stock, feeding the stock, and repeating the operations until the desired amount of stretching is effected to produce fullness only of the stretched area for enabling said area to conform to an elevated portion of a form.

8. A method of treating stock, comprising subjecting an interior portion of the stock to successive stretching operations so as to produce fullness only at the stretched portion upon the completion of said operations, and feeding the stock between such operations.

9. A method of treating stock, comprising subjecting a limited interior portion of the stock remote from its edges to a plurality of tensioning operations, and holding the stock under tension for an interval of time between such operations sufficient to make the stretch permanent.

10. A method of treating stock, comprising tensioning the stock over a limited area located interiorly of and remote from its edge portions, holding the stock under tension sufficiently to make the stretch permanent, releasing the stock, and repeating these operations until the stock has been stretched to the desired extent.

11. A method of treating stock, comprising seizing portions of the stock at spaced points lying within a limited area interiorly of its edge portions, moving the seizing means apart to stretch the area of the stock lying between the points of seizure, holding the stock under tension, for an interval of time sufficient to make the stretch permanent, releasing the stock, feeding the stock, and repeating the stretching operations over a different area.

In testimony whereof we have signed our names to this specification.

ARTHUR L. RUSSELL.
CHARLES E. GRUSH.
